UNITED STATES PATENT OFFICE.

FRANCIS A. ISAACSON, OF OMAHA, NEBRASKA.

WATERPROOF TROUSERS.

SPECIFICATION forming part of Letters Patent No. 608,126, dated July 26, 1898.

Application filed November 9, 1896. Serial No. 611,547. (No model.)

To all whom it may concern:

Be it known that I, FRANCIS A. ISAACSON, a citizen of the United States, residing at Omaha, in the county of Douglas and State of Nebraska, have invented certain new and useful Improvements in Waterproof Garments; and I do hereby declare the following to be a full, clear, and exact description of the invention, such as will enable others skilled in the art to which it appertains to make and use the same.

This invention relates to a novel improvement in waterproof garments.

The object of my invention is to provide waterproof trousers which shall be adapted to be used in conjunction with an ordinary pair of rubber boots and so arranged that the boots may be worn independent of the trousers or that the trousers may be worn independent of the boots; and in the furtherance of this object I provide the trousers at the bottom of the leg with a clamping device, by means of which they can be detachably secured to the boots to make a water-tight connection.

To aid in explaining my invention I make use of the accompanying drawings, in which—

Figure 1 represents a pair of the trousers with boots attached. Fig. 2 represents a partial vertical section of one of the legs thereof on the line 2 2. Fig. 3 is a perspective view of the clamping-ring. Fig. 4 is a detail longitudinal sectional view similar to Fig. 2, showing a modified construction. Fig. 5 is a plan view of the band or ring illustrated in Fig. 3, showing a modified construction.

In all of the figures the same numerals indicate the same part.

1 is a pair of mackintosh or waterproof trousers of a general form and construction well known in the art, in the legs 2 whereof is made a hem 3, inclosing the ring or band 4, comprising two parts or sections 5. A lug 6 is formed on one end of each section 5, its opposite end being tapered to a knife-edge, a short distance back from which is a second lug 6^a. Through each pair of lugs 6 6^a, the lugs being on different sections, is passed a right and left handed screw-bolt 7, which is threaded into the aforesaid lugs. The lugs and bolt as thus arranged form a turnbuckle, by means of which the band 4 is clamped

around the trousers and boot. A thumb-piece 8 on one end of the screw-bolt and a squared portion on the opposite end for a key (not shown) present means for turning the bolt. 55

In a boot 9 of ordinary construction an elliptic or similarly-formed band 10 of metal is cemented or otherwise secured upon the interior of the leg portion and near the top thereof. When both trousers and boot are in place 60 upon the leg, the band 4 is adapted to be slipped over the leg of the boot until it registers with the band 10, when the former is tightened by means of its turnbuckles, already described, forming both a secure and water-tight joint. The tapered end of each section 5, extending across the opening between the lugs 6 6^a, will prevent the trousers from entering between the said lugs, the result of which would be an imperfect joint between 70 the trousers and boot.

In the manufacture of the trousers I prefer a rubber fabric, as the same possesses sufficient elasticity to pass over the boot-leg and conform closely thereto; but I do not confine myself to this material, as by the use of a bellows gusset in the bottom of the trousers-leg I may utilize non-elastic fabrics. 75

The material of the several bands is likewise of non-importance, though I preferably employ one of a stiff yet resilient nature for reasons quite apparent.

Having fully described my invention, what I desire to secure by Letters Patent and claim is—

1. In a waterproof garment, the combination with a pair of trousers, of a fold or hem formed on the lower end of each leg thereof, and means secured in said fold for contracting and expanding the bottom of the trousers-leg, substantially as set forth. 90

2. In a waterproof garment, the combination with a pair of trousers having a hem or fold at the lower end of each leg thereof, of a sectional clamping-band secured within the fold of each leg, and means for expanding and contracting the said band and thereby the bottom of the trousers-leg, substantially as set forth. 95

3. In a waterproof garment, the combination with a pair of trousers formed with an inward fold or hem at the bottom of each leg 100

thereof, of a sectional clamping-band irre-
movably secured within said fold, each sec-
tion having a tapered end which is overlapped
by the butt-end of its adjacent section, and
5 means for expanding and contracting the said
sectional band, and thereby the bottom of the
trousers-leg, substantially as set forth.

In testimony whereof I affix my signature
in presence of two witnesses.

FRANCIS A. ISAACSON.
